WINDOW STRUCTURE

Addison J. Rogers, Cleveland Heights, Ohio

Application April 7, 1937, Serial No. 135,521

5 Claims. (Cl. 20—49)

This invention relates to improvements in window structure.

Windows of the sliding type are often difficult to move because of tight engagement of the sash with the engaged portion of the frame and one of the objects of the present invention is to provide a laterally extensible and retractable sash which by manipulation may be freed from the frame in order to more readily move the same.

10 Great difficulty, expense and danger of injury is incurred in obtaining access to the outside surface of windows of a building structure for purposes of painting, repairs or washing of the glass. An object of the present invention is to facilitate 15 access to the outer surface of sliding windows from within the building. To this end the sash is so mounted in the frame and so constructed that its side portions may be disengaged from the frame, permitting the sash to be moved entirely or partially out of the general plane of the frame and manipulated to bring the outer portion of the sash within reach of a person inside the building. A special form of such construction illustrated provides a pivoted sash with retractable side portions in which the side portions 20 when retracted clear the frame and the sash guides, so that the sash may be turned on its pivot to bring the outer surface thereof within reach of a person inside the building.

25 30 Other features of my invention comprise means for counterweighting the sash in the usual manner, such counterweight means being arranged to exert its effect on the sash at all times. Also means is provided for holding the extensible side portions of the sash in retracted position. Other novel features reside in the specific construction of the parts whereby the extensible side members form substantially rigid lateral extensions of the sash and prevent the entrance of weather.

35 40 Another feature of my invention is the combination of a novel weatherstripping means with a laterally expansible sash.

In the drawings, Fig. 1 is a view in elevation of a double hung window including a frame and 45 upper and lower slidable sash members; Fig. 2 shows the structure of Fig. 1 with both sashes in tilted position; Fig. 3 is a partial longitudinal sectional view through one of the side rails of a sash of Figs. 1 and 2; Fig. 4 is a transverse section through a side rail and a portion of the frame taken generally along the line 4—4 of Fig. 3; Fig. 5 is a sectional view similar to Fig. 4 showing the extensible portion of the sash in retracted position; Figs. 6 and 7 are partial sectional views 50 55 along similarly numbered lines of Fig. 3; Figs. 8

and 9 are detail views showing the attachment of the counterweight cord to the sash pivot pin; Fig. 10 is a detail sectional view showing means for holding the pivot pins in frictional engagement with the frame; while Fig. 11 is a modified form of side member retracting means.

5 10 My invention may be adapted to slidable sash of any sort. For instance, it is equally applicable to metal and wooden sash and to sash of other than rectangular form although I have illustrated the rectangular form as it is by far the most common type.

15 Pivoted sash have heretofore been constructed wherein the stop members normally engaging and sealing the side edges of the sash are discontinuous. For instance, one form of such sash provides an inner stop member on one side of the sash pivot and an outer stop member on the opposite side of the pivot pin. My construction is different from this in that I provide uninterrupted and continuous stops on both the inner 20 and outer faces of the sash. Another form of pivoted sash provides removable stop members which must be moved when the sash is to be pivoted. My invention differs from such construction in that the stop members, both inner and outer, are permanently fixed in place.

25 30 I have illustrated my invention as applied to a common type of window structure comprising a frame 10 in which are slidable upper and lower sashes 11 and 12 respectively. This window structure as is usual is provided with an inner stop 13, an intermediate stop 14 and an outer stop 15. All of these stops are permanently fixed in place and are uninterrupted from top to bottom. 35 The upper sash slides in the frame between the stops 14 and 15 and is provided with a sash cord 16 which is connected to the sash 11 and passes over a pulley 17 and carries at its other end within the frame a counterweight not shown. In a 40 like manner the lower sash 12 slides in the groove between stops 13 and 14 and has a sash cord 18 attached to the lower sash and passing over a pulley 19 and provided with a suitable counterweight.

45 50 While it would be possible to retract one side edge portion of the sash sufficiently to clear the frame and the stop members, to accomplish my purpose I prefer to make opposite side edges of the sash retractable as shown. The construction here shown is similar for both the upper and lower sash and is the same on both sides of a given sash so that the construction of one side edge portion of one of the sashes will be described, it being understood that this description 55

applies to all of the side edges shown. Each side rail of the sash, as for instance the side rail 20, has the main portion thereof cut so that the dimension of the sash from side to side is less than 5 the distance between opposite stop members, that is to say, the main portion of the sash will pass freely through the frame. Opposite side edges of the sash are then provided with strip members 21 preferably of metal and bent so as to coact 10 with the sash in both retracted and extended position so as to form substantially rigid lateral extensible portions of the main sash.

To this end, with the form of sash herein illustrated, the sash rail 20 is rabbeted as at 22 15 to provide a central groove extending longitudinally of each side edge of the sash. The strip 21 is then given a shape corresponding to the section of the sash, as is best shown in Figs. 4 to 7. In this form of construction the side edge 20 portion 21 has parts 21a slidable along the inner and outer faces of the sash rail and having a very slight clearance therefrom of the order of $\frac{1}{64}$ inch. The metal of the strip member then extends outwardly to provide the portions 21b 25 which enter between the stops of the frame. The central portion of the strip member is then bent inwardly to provide the portions 21c which engage the walls of the groove 22. The walls of the groove are substantially parallel with the 30 inner and outer faces of the sash rail and the coacting parts of the strip 21 are correspondingly formed so that the portions 21a and 21c engage like portions of the sash to perform a double function. In the first place the strip is firmly 35 supported so that it provides a substantially rigid extension for the side rail 20, and in the second place the strip parts engaging the main sash seal the structure against weather. The portions 21c are connected by the portion 21d as indicated. Preferably the ends of the strips 21 are closed in by portions 21e at each end, making 40 the side edge portions of a strong box-like character.

By forming the side edge portions in the manner described, I may use a metal of comparatively light gage, say for instance steel of 28 gage, and the longitudinal deformations give sufficient strength to the side edge portions that the sash is as impregnable as the usual sash not provided 50 with my improved features.

The sash may be counterweighted in any suitable manner but in the form shown I have provided alined pivot pins 23 on opposite side edges of the sash secured to the side rails 20 in any suitable manner. For instance, as shown in Figs. 3 and 7, a plate 24 is secured in the sash rail and the pivot pin is threaded in the plate. The sash cord 16 or 18 is secured to the pivot pin 23 55 on each side, the construction being such that the sash may pivot without disturbing the sash cord connection. To this end the pivot pin may be rotatable in the sash rail or the sash cord connection may be rotatable on the pivot pin. I 60 have illustrated this latter structure wherein the cord 16 is secured to the loop 25a of a member 25 which has another loop 25b in a plane normal to the plane of loop 25a and within which the pin 23 rotates. A spring clip 26 is provided to 65 hold the member 25 on the pin 23. The strip member 21 is provided with a suitable opening at 27 to accommodate the pin 23. With this construction the strip 21 may be extended and retracted without interfering with the counterweight means and the sash may be tilted without 70

interfering with the counterweighting as the pin 23 rotates in the loop 25b.

Means is provided for extending and retracting the strip members 21 relative to the associated sash. In the form shown flat springs 28 are provided between the strip members and the sash rail in suitable number and location to bias the strip members outwardly in a uniform manner throughout the length of the sash. For instance a suitable arrangement is the provision of springs 10 in the groove 22 located approximately one-third of the distance from both the upper and lower edges of each sash to the center, that is to say, two springs of the type shown are provided for each side edge portion or strip member 21 for a 15 30" x 30" sash. Suitable means is provided for retracting the side edge portions against the action of springs 28 and these may be suitable handles or clips serving to retract the side edge portions whether or not they are provided with 20 means for holding the side edge portions retracted. One such construction comprises a handle 29 having its ends connected to pins 30 extending through the sash side rails and connected with the side edge portions 21, as for instance by the enlarged heads 31. Upon pulling of the handle 29 inwardly, the connected side edge portion is retracted.

A simple means for holding the side edge portions retracted is shown in Figs. 4 and 5 where 30 cam portions 29a are constructed rigid with the handle 29. As the handle is pivoted about the pivot connection 33a with the pins 30, the cam portion 29b engages against the side rail of the sash and holds the side edge portions 21 in retracted position as shown in Fig. 5. It will be obvious that with the side edge portions 21 in this retracted position they are drawn in sufficiently to clear the stops 14 and 15 or 13 and 14 as the case may be, permitting the sash to pivot 40 about the pins 23. Each sash may thus be turned inside out, giving easy access to the outer portion of the sash from the interior of the building. When the side edge portions are again extended they engage within the frame 10 and support 45 the sash for the ordinary sliding movement.

Combined with my laterally extensible sash I may provide a very efficient weather strip. This is indicated in Figs. 4 to 7 and may comprise one or two L-shaped metal strips 32 having 50 a leg 32a secured to the frame 10 and a leg 32b yieldingly engaging against that portion of the strip member 21 which extends inwardly to provide the portions 21c. A seal is thus provided at the point 32c in any of the adjusted positions of 55 the sash and, as illustrated, with two such weather strip members 32 a double seal is provided.

Means may be provided, if desired, to hold the pivot pins 23 in place relative to the frame while 60 the sash is pivoted. One such device is shown at 33 in Fig. 10. A thimble portion 33a of the device embraces the end of pin 23. A base portion 33b comprises a plate narrow enough to fit between the strip portions 21c and as long as desired. A spring 34 biases the device 33 into frictional engagement with the frame 10.

A modified form of side-portion retracting means is shown in Fig. 11. Spaced along the sash rail are the members 35. The retracting 70 pin 30 has the same function as the pins 30 previously described. A projection 36 at the inner end of the pin enters the cam slot 37 in slide 38. This slide has guides 39 secured to the sash and may be moved by handle 40. By pulling the slide 75

downward the pin 30 is cammed inward and retracts that portion of member 21 connected therewith. These devices 35 render it easy to retract the side edge portions and to hold them retracted while the sash is tilted.

5 What I claim is:

1. In a window structure, a sash, a frame having portions adjacent opposite side edges of said sash, each of said opposite side edges of said sash having inner and outer parallel faces and a groove between said faces extending longitudinally of each side edge, said groove having walls parallel to said faces, and a metal strip member coextensive with each side edge and normally spaced therefrom, each strip member having parts engaging said parallel faces and walls, spring means normally maintaining said strip members in extended position, said frame having inner and outer stops engaging said members in said extended position, counterweight means for said sash, and means for retracting said strip members to clear said stops.

2. In a window structure, the combination of claim 1 including an uninterrupted weather strip coextensive with a side edge of said sash and engaging said frame and one of the walls of said groove.

3. In a window structure, a frame, a sash slideable in said frame, said sash having a main portion and retractable side edge portions on opposite side edges of said main portion, aligned pivot pins secured to opposite side edges of said sash, a member carried by each pivot pin and having a flat surface adapted frictionally to engage said frame, and a spring between each pin and its associated member for holding each member in engagement with said frame.

4. In a window structure, a frame, a sash slideable in said frame, said sash having a main portion and laterally extensible edge portions on opposite side edges of said main portion and substantially coextensive with said side edges, each side edge portion being a single sheet of metal

directly engaging said frame when in extended position, said frame having substantially uninterrupted stops engaging the outer and inner faces of each side edge portion when said portions are in extended position, the parts being so arranged that said edge portions in retracted position clear said stops, said side edge portions having parts closely engaging the inner and outer faces of said main sash portion throughout the length of said side edges for substantially sealing the joint between said side edges and edge portions and for holding said edge portions in extended position substantially rigidly aligned with said main sash portion, aligned pins on said opposite side edges of said main sash portion 15 and secured thereto and extending outwardly through the associated side edge portion, counterweights secured to said pins, and means for extending and retracting said side edge portions.

5. In a window structure, a sash having opposite parallel side edges, a frame parallel to said sash adjacent each side edge, said frame having inner and outer stops for guiding said sash, said sash being of less width than the distance between said stops from side to side of said frame, a strip member along each side edge of said sash, each strip member having free edge portions coextensive with said sash slidably and closely engaging the inner and outer faces of the sash, each said member being adapted with said edge portions engaging the sash to be extended outwardly between the stops of the frame, means for extending and retracting said strip members, aligned pins one on each side of said sash and secured thereto, each strip member having an 30 inwardly extending centrally located longitudinal groove running at least from each pin to the top of the sash, a sash cord secured to each pin and extending along said groove in the associated strip member, and a counterweight se- 40 cured to each sash cord.

ADDISON J. ROGERS.
